UNITED STATES PATENT OFFICE.

HERBERT DAVID JACKSON, OF WALSALL, ENGLAND.

GUARD FOR PRESSES, STAMPS, AND LIKE MACHINES.

Application filed March 21, 1923. Serial No. 626,588.

To all whom it may concern:

Be it known that I, HERBERT DAVID JACKSON, subject of the King of Great Britain, of Summit Works, Hospital Street, Walsall, 5 Staffordshire, England, have invented certain new and useful Improvements in and Relating to Guards for Presses, Stamps, and like Machines, of which the following is a specification.

10 This invention relates to improvements in guards for power presses, stamps, and like tools, and refers particularly to an improved guard which is adapted to obviate any possibility of injury to the operator 15 during a working stroke of the press or the like.

In the usual type of press or stamp a pulley is continuously driven by belting or like means and is temporarily clutched to 20 the cross shaft which carries the press-operating eccentric or like means by a key or other clutch which is thrown into engagement when a lever is depressed by the operator.

25 A fixed guard is generally provided on the left of the tools or dies so that the operator must place the blank upon the fixed die with the right hand which is also used for depressing the lever, and in theory 30 safety is thus obtained since the lever cannot be depressed while the operator's fingers are between the dies.

It has also been proposed to provide a 35 sliding guard which is moved into position in front of the dies when the lever is depressed, but both of these methods fail to guard against the possibility of defects developing in the clutch mechanism, or of the press being given two working strokes 40 for one depression of the lever either through the clutch key becoming worn, or through backlash developing in the lever mechanism, and as the guard in the latter case only protects the dies when the lever 45 is depressed injury to the operator may easily occur.

Guards have also been proposed which are brought into operation by the moving die as it descends on its working stroke, 50 but such guards do not come into the full

operative position until the die has moved a considerable distance, and also, owing to the rapid motion of the die, the movement of the guard itself is rapid and may cause injury to the fingers of the operator.

55 The object of my invention is to provide an improved guard for power presses, stamps and like machines, in which the guard is independent of the clutch or operating lever, and is positively brought into 60 action by the rotation of the cross shaft so that the moving die cannot descend without being protected by the guard, and the possibility of accidental injury to the operator is eliminated.

65 A further object of my invention is to provide a guard which is brought into its active position before the moving die has travelled an appreciable distance on its working stroke and which protects the dies 70 until the moving die is near the end of its return stroke.

75 This is particularly important for drawing dies where the moving die enters a considerable distance into the fixed die and the clearance between the dies in the inoperative position is not great.

With these objects in view my invention 80 essentially comprises a guard for power presses, stamps, and like machines, in which a guard member adapted to protect the tools or dies during the working stroke is carried by a reciprocating member which is slidably mounted on the bed of the press or the like 85 and is moved into the operative position by a lever and cam mechanism from the cross or driving shaft of the press as the movable die begins its working stroke and is withdrawn by a spring as the die reaches the end of its return stroke, the striking 90 face of the cam being arranged at such an angle that the guard is moved into the fully operative position before the die has moved an appreciable distance on the working stroke.

95 My improved guard may be arranged in a variety of ways to adapt it for use on different types of presses, but one preferred embodiment, which is suitable for a variety 100 of presses, has been illustrated by way of

example in the accompanying drawings in which:—

Figure 1 is a plan of the guard operating mechanism showing the guard in its retracted position in full lines and in the forward or operative position in dotted lines.

Figure 2, is a front elevation.

Figure 3, is a diagrammatic end elevation of the complete guard showing the lever and cam mechanism.

Figure 4, is a diagrammatic front elevation showing, in full and dotted lines respectively, the guard in the retracted and operative positions relative to the dies.

15 In the drawings *a* is the guard member which may conveniently be formed of sheet metal of a suitable size and shape corresponding to the dies with which it is used, and having its forward end curved round 20 as shown at *a'* in Fig. 1 to prevent injury to the operator's hand if the guard should come into contact with it.

The guard is secured by bolts *b* to a rectangular reciprocating member *c* which is 25 slidably mounted between and guided by three pairs of vertical rollers *d* upon a base plate *e* secured to the bed of the press by bolts *e'*.

The member *c* is horizontally slotted for 30 a portion of its length as shown at *c'* and within this slot is housed a flat slide cam or wedge member *f* of substantially triangular outline as shown in Fig. 1. The rear edge of the member *f* is at right angles to the reciprocating member *c* and bears against one pair of the rollers *d*, while the front edge is 35 inclined at an angle of, say, 45° and bears against a roller *g* carried on a vertical pivot at the forward end of the slot *c'*. A tension spring *h* is connected between a pin *j* on the reciprocating member *c* and a pin *k* on the bridge piece for the outer pair of rollers *d* or any other convenient fixed point and 40 serves to retain the member *c* normally in the retracted position shown in full lines in Fig. 1.

The member *f* has an integral boss *f'* into 45 which is screwed one end of a horizontal rod *l* at the other end of which is a forked head *m* within which is pivoted the lower end of a substantially vertical lever *n*. This lever is pivoted at *p* upon the frame of the press and carries at its upper end a roller *q* engaging a cam *r* on the cross or driving shaft *s* of the press. The cam is preferably 50 of an outline substantially similar to that illustrated in Fig. 3, and is keyed upon the shaft *s* in such a position relative to the crank or eccentric by which the moving die of 55 the press or eccentric is reciprocated that the cam lifts the roller *q* and moves the upper end of the lever *n* outwards as the crank or eccentric moves over top dead centre on the working stroke, and as the movement of

the die during this part of the stroke is negligible, the cam brings the guard into the operative position before the die has moved downwards an appreciable distance. Thus for all positions of the moving die except at the upper limit of its movement on the 70 return stroke the dies are covered by the guard.

The action of the device will be readily followed from the drawings.

As the moving die approaches the upper 75 limit of its movement on the return stroke the roller *q* rides off the cam *r* and the wedge member *f* together with the rod *l* and the lower end of the lever *n* is free to move to the right in Fig. 3 under the influence of the spring *h* which retracts the member *c* and with it the guard *a* into the position shown in full lines in Fig. 4. The dies *t* are thus 80 uncovered and a blank can be placed in position on the fixed die. When the press clutch is engaged and the shaft *s* commences to rotate, the cam engages the roller *q* and rocks the lever *n* about its pivot so that the lower end of the lever is carried to the left in Fig. 3 taking with it the rod *l* and the wedge member *f* which in turn moves the reciprocating member *c* forward to bring the guard into the operative position as 85 shown in dotted lines in Fig. 4. All danger of the operator's fingers being trapped between the dies is therefore eliminated. Small bolts and washers *u* may be provided on the edge of the wedge member *f* parallel to the reciprocating member *c* to form a 90 stop for the member *f* and prevent it from being completely withdrawn from the slot in the member *c* by a too violent actuation of the lever *n*, but these are not essential in 95 all cases.

I claim:—

1. A guard for power-presses, stamps, and like machines, comprising a guided reciprocating member, a guard member carried by the said reciprocating member, resilient means for retaining the reciprocating member normally in the inoperative position, and positive means operated from the driving shaft of the machine for bringing the reciprocating member into the operative position as the moving die of the machine begins its working stroke, the said means comprising a cam on the driving shaft, a pivoted lever of which one end is engaged by the said cam, and a wedge member which is connected to the other end of the pivoted lever and slides within a slot in the reciprocating member.

2. A guard for power presses, stamps, and like machines, comprising a reciprocating member, a guard member carried by the said reciprocating member, a base plate, pairs of fixed rollers on the said base plate between which rollers the said reciprocating member

is slidably guided, a wedge member of substantially triangular outline adapted to slide in a slot in the reciprocating member and abutting between one pair of fixed rollers 5 and a roller at one end of the slot, a lever pivoted upon the frame of the machine, a horizontal rod connecting the lower end of the said lever to the said wedge member, a

roller at the upper end of said lever, a cam which is adapted to engage the said roller 10 and is keyed upon the driving shaft of the machine, and a spring which effects the return movement of the reciprocating member.

In testimony whereof I affix my signature.

HERBERT DAVID JACKSON.
